US0D1003064S

(12) **United States Design Patent** (10) **Patent No.:** **US D1,003,064 S**
(45) **Date of Patent:** **** Oct. 31, 2023**

(54) **VEHICLE ROW SEATS**

(71) Applicant: **JAGUAR LAND ROVER LIMITED**,
Coventry (GB)
(72) Inventor: **Richard Carter**, Coventry (GB)
(73) Assignee: **JAGUAR LAND ROVER LIMITED**,
Coventry (GB)

(**) Term: **15 Years**

(21) Appl. No.: **29/782,847**

(22) Filed: **May 10, 2021**

(30) **Foreign Application Priority Data**

Nov. 10, 2020 (EM) 008262729-0001

(51) **LOC (14) Cl.** **06-01**

(52) **U.S. Cl.**
